AIR CLEANER FOR CRANK CASE VENTILATION

Filed Sept. 22, 1927

UNITED STATES PATENT OFFICE

CLINTON H. DEARBORN, OF HAMPTON, VIRGINIA, ASSIGNOR TO A C SPARK PLUG COMPANY, OF FLINT, MICHIGAN, A COMPANY OF MICHIGAN

AIR CLEANER FOR CRANK-CASE VENTILATION

Application filed September 22, 1927. Serial No. 221,302.

The present invention relates to internal combustion engines and more particularly to an air filter used with the inlet opening in the engine crankcase.

5 It is an object of this invention to provide an air cleaner for use with the filler pipe in the engine crankcase. It is a further object of this invention to provide such a cleaner that will effectively clean the air entering for ventilation of the crankcase and yet which will not interfere with the normal use of filler opening.

Other objects and advantages of the invention will appear in the course of the following description, taken in connection with the accompanying drawing and appended claims.

In the drawing:

Figure 1 is a side elevation showing the 20 arrangement of my improved air filter on a conventional internal combustion engine.

Figure 2 is an enlarged longitudinal section through the filter and oil inlet.

Figure 3 is a front view of the perforated 25 cover for the filter.

Referring to the drawing, the numeral 10 indicates a conventional internal combustion engine in the side of the crankcase of which is the oil filler pipe 12. Stamping 14 30 is fixed about the mouth of the filler pipe by any usual means and is formed on its forward side to provide a bearing 16 for a pivot pin 18 on which is hinged the filter cap 20.

The filter cap 20 is provided intermediate 35 its ends with a perforated disk 22 and is provided on its rear end with the perforated cover disk 24 which is crimped about the flanged rim 26 of the cap 20 as illustrated. Between the two disks is the filtering material 28 which may be of any desired fibrous material such as steel wool. Flange 32 is provided on the filter cap 20 and fits about the gasket 30 which rests on the rim of the pipe 12 and on the stamping 14. A spring latch 40 45 34 is fixed to the under side of the filter cap 20 and is adapted to slide over the stamping 14 and hold the cap firmly in position to close the filler pipe.

In the use of the device the filter cap 20 50 functions just the same as any other cap

would and may be swung to open or close the entrance to the pipe 12. During operation of the engine, the cap 20 functions as a breather and dust particles passing through the filter cap 20 are removed by the filtering material 28.

I claim:

1. The combination of a crankcase provided with an oil filler opening, a pivoted closure for said opening, said closure being apertured for the admission of air to the crankcase when the closure is in closed position, and a body of filtering material in said closure for cleaning the air passing therethrough to the crankcase.

2. The combination with a crankcase provided with an oil filler tube, a fitting therefor, comprising a member adapted to be secured to the tube, a tubular casing pivoted to said member, means carried by said casing for engaging the member to hold it in closed position, and a filtering medium in said tube for cleaning air passing therethrough to the crankcase.

3. In the combination as defined in claim 2, said member being provided with an enlarged outer portion for receiving a gasket to be engaged by the adjacent end of the casing when the latter is in closed position.

4. In the combination as defined in claim 2, 80 said casing being provided with spaced apertured members between which said filtering medium is confined.

5. The combination of a crankcase provided with an oil filler tube, a tubular member pivoted to the tube, means for detachably securing the member in closed position, a pair of spaced apertured members in the outer end of the tubular member and a body of filtering 90 material between the spaced members for filtering the air passing into the crankcase.

6. The combination of a crankcase provided with an oil filler tube, a tubular member pivoted to the tube, means for detachably securing the member in closed position, an apertured plate crimped over the outer end of the tube, a foraminous member secured within the tube and spaced from the plate and a body of filtering material between the 100

members for filtering the air passing into the crankcase.

7. A fitting for the oil filler tube of an engine crankcase comprising an annular member adapted to encircle the oil filler tube and provided at one end with a flange serving as a gasket seat and with a hinge member, a gasket on the seat, a tubular member pivoted to the hinge member and provided with a flange adapted to engage the gasket, means for detachably connecting the tubular member and the annular member in sealing relation, and a body of filtering material secured within the tubular member and adapted to filter the air passing into the crankcase.

In testimony whereof I affix my signature.
CLINTON H. DEARBORN.
